UNITED STATES PATENT OFFICE.

HENRY G. VOIGHT, OF NEW BRITAIN, CONNECTICUT, ASSIGNOR TO THE RUSSELL & ERWIN MANUFACTURING COMPANY, OF SAME PLACE.

DESIGN FOR A LATCH OR LOCK CASE.

SPECIFICATION forming part of Design No. 30,845, dated May 23, 1898.

Application filed February 20, 1899. Serial No. 706,265. Term of patent 14 years.

To all whom it may concern:

Be it known that I, HENRY G. VOIGHT, a citizen of the United States, residing at New Britain, in the county of Hartford and State of Connecticut, have invented and produced 5 a new and original Design for the Case of a Latch or Lock, of which the following is a specification, reference being had to the accompanying drawings, in which—

10 Figure 1 is a plan view of a latch or lock case, showing my new design; and Fig. 2 is a cabinet perspective of the same with features of the case which are older than my invention represented in broken lines.

15 As shown in the drawings, A designates the body-case, and B the cap, which in the complete latch or lock case are secured together, as shown. There is nothing peculiar to my design except the shape of the confronting edges 20 of the case-body and cap, as seen at the upper and lower edges of the case, and consequently I have represented the other faces, which are old, by broken lines, while the characteristic features of the design are distinctly 25 illustrated by the full lines.

The confronting edges of the metal in the cap and case-body are mainly on a straight line 2, with an oblique recess 3 in the case-body near the face-plate, the bottom of said recess being a half-circle. The overhanging 30 edge or projection on the shorter side of said recess is rounded off gently, as at 4, while the junction of the lower side of said recess with the edge of the metal in the case-body is also rounded off, as at 5. At the inner edge of the 35 case-body there is a projection 6 beyond the straight line 2. The confronting edge of the metal in the cap is the counterpart of that in body, a rounded projection 7 filling the recess 3, and a recess 8 in the cap receiving the projection 6 of the case-body, all as shown.

Having described my invention, what I claim as new, and desire to secure by Letters Patent, is—

The design for a latch or lock case as here- 45 in shown and described.

HENRY G. VOIGHT.
